Attorney

UNITED STATES PATENT OFFICE

FREDRICK ANWAY, OF GENEVA, IOWA

STAPLE CLINCHER

Application filed January 24, 1931. Serial No. 510,872.

My invention relates to staple clinchers and the main object is to provide a tool with which the staples used in connection with the conventional metal fence posts of T cross section may be readily and efficiently bent or clinched around the post to hold the fence in place.

Another object is to provide a tool of the above character in a simple, durable and efficient form.

The foregoing and other objects together with means whereby the same may be carried into effect will best be understood from the following description of a preferred embodiment of my invention taken in connection with the accompanying drawings wherein:

Figure 1 is a plan view of the tool as in use for clinching a staple around a post, the 20 staple and post being shown in broken lines.

Figure 2 is an edge view of the tool alone, a part of the handle being broken away.

Figure 3 is a section along the line 3—3 in Figure 1.

Figure 4 is a section along the line 4—4 in Figure 1.

Figure 5 is a detail view of a modification of the jaw member of the tool.

Referring now more particularly to the drawings the reference numeral 1 designates a metal fence post of conventional form and T-shaped in cross section, the said post comprising the forward member or bar 2 and the rear web 3 set at the rear thereof and extended therefrom at right angles as shown. To secure the fence (not shown) to the post 1 wire staples are provided, one of which is shown at 4, each staple comprising a hooked end 5 to fit around one margin of the forward bar 2, a knee 6 to pass across the front of the forward bar and to enclose or straddle one of the line wires of the fence. The remainder of the staple is then bent angularly backward to provide the leg 7 which in conventional practice is bent around the rear edge of the rear web 3 as shown at 8 by means of a hammer or the like. The foregoing elements and their arrangement and operation are conventional.

My invention comprises a jaw 9 including

the leg 10, and the knee 11 extended at an acute angle from the leg and terminating in the hooked end 12, the jaw being thus substantially the same shape as the staple 4 which it is to receive. A handle 13 is hinged 55 at 14 to the end of the leg 10 remote from the knee 11 and an ear or head 15 is provided at the end of the handle adjacent its hinged connection to the jaw. The inner face of the jaw has a medial groove 16 longitudinally 60 extended throughout its length and a keeper or socket member 17 is mounted on the leg 10 between the knee 11 and the hinged connection 14 of the handle 13. This keeper or socket member 17 as here shown may be 65 formed of a strip of material bent at its ends 18 around the margins of the leg 10 and bent outward and then back toward the leg at 19 intermediate its ends to provide a socket or cleft 20 to receive the leg 7 of the 70 staple 4. The keeper might also be formed integrally with the jaw if so desired. In use the staple 4 is placed in the jaw 9 where it rests in the groove 16 and cleft 20 secure against lateral displacement. The staple 75 is then placed around the forward member 2 of the post 1 still within the jaw and of course across the fence wire (not shown). The head 15 of the handle 13 is then brought to bear upon the rearwardly extended end of 80 the staple leg 7 by a rearward movement of the free end of the handle and a continuation of this rearward movement of the handle will cause the head 15 to bend the said rear end of the staple around the rear edge of the web 85 3 of the post thus clinching the staple. The tool may be released from the staple by returning the handle forwardly and slipping the tool around the post slightly until the hooked end 12 thereof is disengaged as will 90 be understood. It will be noted that the staple does not extend fully into the corner formed by the junction of the jaw leg 10 and knee 11, thus allowing the jaw to move rearwardly and toward the post's rear web 3 as 95 the staple leg 7 is bent over and around the said web. The removal of the tool from the staple is also facilitated by this arrangement and to further render the removal of the tool convenient the groove 16 is made consider- 100

ably deeper adjacent the hooked end 12 of the jaw as shown at 21 thus allowing a freer movement of the jaw as described. A flat or leaf spring 22 may be mounted in the corner 5 of the jaw and at the same time normally hold the staple against the forward member 2 of the fence post until the staple is fully clinched. This construction is shown in Figure 5.

10 From the foregoing it will be apparent that I have provided a simple and readily operated tool with which the staples may be conveniently and quickly clinched in place, the staple being held tight against the fence 15 wire until it is clinched.

While I have herein set forth a certain preferred embodiment of my invention it is understood that I may vary from the same in minor structural details, now departing 20 from the spirit of the invention and within the scope of the appended claim.

I claim:

In a tool of the kind described, a jaw including a leg portion, a knee portion hooked 25 at its end and extended from the leg portion at an acute angle thereto, a handle hinged to the end of the leg portion remote from the said knee portion, and a head extended from the handle at its hinged end, the said jaw 30 having a longitudinal staple receiving groove formed in its inner face from end to end, and a keeper on the leg portion of the jaw, the said keeper having a centrally disposed staple receiving cleft.

35 In testimony whereof I affix my signature.
FREDRICK ANWAY.
